Patented Jan. 23, 1973

226,109

STYLIZED MODEL DRAGSTER

Eugene T. Daniel, Walnut, Calif., assignor to Mattel, Inc., Hawthorne, Calif.

Filed June 21, 1971, Ser. No. 155,406

Term of patent 14 years

Int. Cl. D21—01

U.S. Cl. D34—15 AJ

Des. 226,109

PAGE 2

FIG. 1 is a right side elevational view of a stylized model dragster showing my new design;

FIG. 2 is a front elevational view thereof;

FIG. 3 is a left side elevational view thereof;

FIG. 4 is a rear elevational view thereof;

FIG. 5 is a top plan view thereof;

FIG. 6 is a bottom plan view thereof.

I claim:

The ornamental design for a stylized model dragster, as shown and described.
